(57) **CLAIM**

The ornamental design for a shoe upper with lacing system, as shown and described.

DESCRIPTION

FIG. 1 is a top view of a shoe upper with lacing system showing my new design;

FIG. 2 is a side view thereof;

FIG. 3 is a second side view thereof;

FIG. 4 is a toe end view thereof; and,

FIG. 5 is a front perspective view thereof.

The broken lines immediately adjacent to and surrounding the shaded areas represent unclaimed boundaries of the design. The broken lines showing the remainder of the shoe are for environmental purposes only and form no part of the claimed design.
